ABSTRACT: A casing is provided in one side with a cigarette receptacle and in its other side with a compartment adapted to receive a container of CO₂ gas. Above the cigarette receptacle is a tube for the insertion of cigarettes and flap gates adapted to be opened to drop the cigarette into the receptacle, whereupon a valve operating button is pressed to discharge CO₂ gas into the receptacle to extinguish the cigarette.

FIG. 1

FIG. 4

FIG. 2

FIG. 3

INVENTOR.
MARVIN J. BLAKEWAY
BY Alexander B. Blair
ATTORNEY.

CIGARETTE RECEIVER AND EXTINGUISHER

BACKGROUND OF THE INVENTION

It is the common practice to provide receptacles for lighted cigarettes wherein flap gates are provided, adapted to be opened to drop the cigarette into the receptacle. These cigarettes, however, are not extinguished and may continue to smolder for a substantial length of time. These devices are provided with no means for completely extinguishing the cigarette in the receptacle.

Summary of the Invention

The device comprises a casing divided transversely by a wall to form in one side a compartment to receive a container of CO₂ gas, preferably colored, for a reason to be described. In the other side of the partition is a cigarette receptacle having a sight glass in one wall through which the accumulation of cigarettes may be viewed and through which it may be determined through the coloring of the CO₂ gas whether the container for such gas is exhausted. Flap gates are arranged at the top of the cigarette receptacle and a tube is provided to receive cigarettes dropped thereinto. Upon the dropping of a cigarette, a button is pushed to open the flap gates so that the cigarette falls into the receptacle, whereupon a valve-operating button above the gas receptacle is pressed to discharge CO₂ gas into the bottom of the cigarette receptacle. As is well known, CO₂ gas is heavier than air and will not support combustion, and the flow of CO₂ gas into the receptacle maintains a quantity of such gas therein to extinguish completely the lighted cigarettes.

BRIEF DESCRIPTION OF THE DRAWING

FIG. 1 is a plan view of the device;
 FIG. 2 is a vertical section on line 2-2 of FIG. 1;
 FIG. 3 is a transverse vertical sectional view on line 3-3 of FIG. 1;
 FIG. 3 is a transverse vertical view on line 3-3 of FIG. 1; and
 FIG. 4 is a horizontal section on line 4-4 of FIG. 3

DESCRIPTION OF THE PREFERRED EMBODIMENT

Referring particularly to FIG. 2, the numeral 10 designates the casing of the device as a whole comprising a bottom section 12 vented as at 13, and a top section 14. The top section is separable and is normally clamped to the bottom section by conventional clamps 16.

The casing is divided transversely by a vertical wall or partition 18 forming to one side thereof a compartment 20 normally having therein a container 22 for CO₂ gas having a rubber or similar membrane 24 thereacross to seal it. The container 22 has an upwardly extending neck 26 on which is mounted a conventional valve 28 operable by a pushbutton 30 projecting through the top wall 32 of the casing. The valve is inserted by moving the container upwardly therebeneath, and the membrane 24 is punctured by a hollow needle 34 carried by the valve. Upon depression of the button 30, CO₂ gas will be discharged through a flexible hose 36. It should be understood that the gas in the container 22 is maintained at relatively low pressure so that the gas will not be discharged in the manner described below in a high-speed jet.

The casing to the right of the partition 18 in FIG. 2 forms a cigarette receptacle 38 having a sight glass 40 in one wall thereof extending throughout the greater portion of the height of the receptacle.

The top of the receptacle 38 is formed by a pair of flap gates 42 having projections 44 (FIG. 4) for pivoting the flap gates to an end wall 46 of the casing and to the partition 18. These pivots are toward the dividing line 48 between the flap gates so that the latter are over-balanced to be biased by gravity to closed position, as shown in solid lines in FIG. 3, the remote edges of the gates bearing on stops 50.

An actuator is provided for the flap gates in the form of a tapered number 52 adapted to move downwardly between the

flap gates at the line 48 to tilt the gates to the dotted line position shown in FIG. 3. This actuator is carried by a vertical stem 54 having an operating pushbutton 56 slidable in a guide 58 carried by the top wall 32. To the right of the gate operating device in FIG. 2 is arranged a tube 60 having its end projecting through and fixed to the wall 32 and its lower end terminating above the gates 42. When a cigarette is to be disposed of, it may be dropped lighted end downwardly, into the tube 60, whereupon the button 56 is depressed to open the gates 42 to drop the cigarette into the receptacle 38. The axis of the tube 60 is directly above the line 48 (FIG. 1) and accordingly, the cigarette will drop between the spaced adjacent ends of the gates 42 when the latter are in open position.

It will be noted that the hose 36 extends through the partition 18 to discharge CO₂ gas into the receptacle 38. The CO₂ receptacle is inserted from beneath the valve 28 with the upper casing section 14 is removed, and the hollow needle 34 will puncture the membrane 24. The button 30 is pushed to admit CO₂ gas through the needle 34 to the valve mechanism 28 and thence through tube 36 to the receptacle 38. After a cigarette is dropped into the tube 60 and the button 56 pushed downwardly to open the gates 42, the lighted cigarette will drop into the receptacle 38 whereupon the pushbutton 56 is released. The CO₂ gas, admitted into the receptacle 38, at low pressure, will settle into the bottom thereof and immediately extinguish the cigarette. If the gas is colored, it can be viewed through the sight glass 40 to determine that each cigarette dropped into the receptacle will be immersed into the gas to be extinguished. By looking through the glass 40 whenever the button 30 is pressed, it can be determined whether more gas is flowing into the receptacle or the container 22 is empty. Upon admission of gas in to the receptacle 38, displaced air will be discharged through the vent opening 13. Thus, it will be apparent that the present device provides for the instantaneous extinguishing of cigarettes dropped into the receptacle, thus preventing the cigarettes from continuing to smolder.

While it is preferred to use CO₂ gas, it will be apparent that any inert gas, heavier than air which will not support combustion, may be used with the device.

From the foregoing it will now seem that there is herein provided an improved cigarette receiver and extinguisher which accomplishes all of the objects of the invention and others, including many advantages of great practical utility and commercial importance.

As various embodiments may be made of this inventive concept, and as many modifications may be made in the embodiment hereinbefore shown and described, it is to be understood that all matter herein is to be interpreted merely as illustrative and not in a limiting sense.

I claim:

1. A cigarette receiver and extinguisher comprising a casing having a receptacle therein, closure means at the top of said receptacle adapted to be opened to drop a lighted cigarette thereinto, and means for supplying to said receptacle an inert noncombustion-supporting gas which is heavier than air to form a layer of such gas in the bottom of said receptacle to extinguish a cigarette dropped thereinto said casing including a compartment, a container for said inert gas in said compartment having a control valve and a tube leading therefrom into said receptacle, and means for operating said valve to discharge gas from said container into said receptacle.

2. A device according to claim 1 wherein said casing is provided with a partition forming one wall of said receptacle and combining with portions of said casing to form said compartment, said tube extending through said partition.

3. A device according to claim 2 wherein said casing is provided with a top wall, said means for operating said valve comprising a button projecting through said top wall.

4. A device according to claim 3 wherein said casing is divided horizontally to form top and bottom portions normally clamped together, said top portion being removable for the insertion and removal of said container.

5. A device according to claim 1 wherein one wall of said receptacle is provided with a sight glass.

6. A device according to claim 4 wherein one wall of said bottom portion of said casing is provided with a vertical sight

glass extending close to the bottom of said receptacle for the viewing of the contents thereof.
